BAND PASS FILTERS

Milton Dishal, Nutley, N. J., assignor to International Telephone and Telegraph Corporation, a corporation of Maryland

Application December 1, 1951, Serial No. 259,382

19 Claims. (Cl. 333—73)

This invention relates to filters, and more particularly to VHF, UHF, and microwave band pass filters of the cavity resonator type having high rates of cut-off.

It has been understood by those skilled in the art for many years that filter networks whose transfer impedance or admittance have both poles and zeros can be designed to produce higher rates of cut-off than is possible with comparable networks having only poles and no zeros. For instance, *m*-derived filter configurations are capable of greater rates of cut-off than comparable constant-*k* configurations. When operating in the VHF, UHF, and microwave region, it has been further understood that band pass filters are usually required to supply small percentage pass bands, and to successfully meet this requirement, the ratios between the reactances, as measured at the mid frequency, of all the various elements in the configuration must conform to rigid tolerances. An equivalent concept is embodied in the statement that the resonant frequency of each resonator and the coefficients of coupling between resonators must conform to rigid tolerances.

Heretofore, it has been attempted to provide VHF, UHF, and microwave band pass filters having a high rate of cut-off due to zeros in the transfer characteristic by utilizing the old well-known configurations and concepts of standard filter theory. This has resulted in circuits having both a configuration and required reactance ratios, that are not practicable obtained.

It is one of the objectives of the present invention to provide a band pass filter having both a configuration and the required reactance ratios which are practicable to obtain and having provisions to vary the resonant frequency of such a configuration to accommodate a range of frequencies in the VHF, UHF, and microwave region. By employing coaxial or cavity resonators which are analogous to a low frequency resonant circuit with each resonator correctly coupled to the following resonator either magnetically or electrically, I provide a band pass filter operable in this VHF, UHF, and microwave region. The dimensions of the cavity resonator are so selected that it will resonate at a desired frequency, or means may be provided to produce resonance at the desired frequency. The dimensions of the coupling openings between adjacent resonators produces the correct coefficient of coupling between adjacent resonators. Therefore, by properly adjusting the resonators' resonant frequency and the coefficients of coupling between adjacent resonators and the coupling of the generator and load to the first and last resonators, respectively, a transfer characteristic is obtained having complex frequency poles.

Another object of this invention is to provide a filter system having both poles and zeros in the transfer characteristic to produce a high rate of cut-off. This object is obtained by carrying the aforementioned filter network one step further to introduce zeros and thereby provide a high rate of cut-off similar to that obtained with an *m*-derived filter configuration. These zeros or infinite at-

2

tenuation points are provided by two coupling lines between alternate cavities of a filter configuration. Thus, in addition to the regular coupling connection between adjacent resonators, alternate resonators to which coupling lines are connected have a pair of probe type couplings for each pair of coupling lines which connect to them. Due to the fact that it is possible to get oppositely phased inductive probes, there are four different combinations that can be used to make up the above mentioned two pairs of probes and their coupling lines. The required electrical length of the coupling lines between alternate resonators will depend upon the probe combinations employed in each of the alternate resonators. In general, including the end effects of the probes, the coupling lines will be some multiple of a quarter wavelength long. The basic requirement for the probe combinations and their associated coupling lines is that, one line shall produce between the two resonators a net capacitive type coupling which is essentially constant over the frequency band for which the filter is to be used, and the other line shall produce between the two resonators a net constant inductive type coupling and the two types of coupling shall be essentially equal in magnitude. The plurality of cavity resonators may be any desired number with the restriction that the aforementioned coupling lines must couple alternate cavities in the manner indicated and no coupling lines may by-pass energy past other coupling lines. An explanation of the production of zeros is that at some frequencies there is a 180° phase difference between the net current injected into the alternate cavity by the coupling lines and the current injected through the intermediate cavity, the two currents then cancelling if the couplings are properly adjusted by selection of the proper dimensions and mode of operation in waveguide resonators.

The above-mentioned and other features and objects of this invention and the manner of attaining them will be best understood by reference to the following description of embodiments of the invention taken in conjunction with the accompanying drawings, wherein:

Fig. 1 is a longitudinal cross-section view of a band pass filter operable in the VHF, UHF, and microwave regions in accordance with the principles of this invention;

Fig. 2 is a cross-section view partly in elevation along line 2—2 on Fig. 1;

Fig. 3 shows the response curves for the band pass filter, one with and the other without zeros; and

Figs. 4, 5, 6, and 7 are longitudinal cross-section views of band pass filters each showing a different embodiment of the invention.

Referring to Figs. 1 and 2 of the drawing, a band pass filter capable of operating in the VHF, UHF, and microwave regions is shown as comprising five coaxial resonators 1, 2, 3, 4, and 5 having tuning slugs 6, 7, 8, 9, and 10 therein. Cavity resonator 1 with its tuning slug 6 will be described in detail in relation to its configuration which will suffice as a description for cavity resonators 2, 3, 4, and 5 since all resonators herein employed are similar.

Resonator 1 is considered coaxial due to the inclusion of tuning slug 6 in the cavity. Tuning slug 6 behaves similar to the center conductor of a coaxial line while the walls of resonator 1 behave as the outer conductor of such a coaxial line in respect to the capacitive or electric field present therebetween. Besides the electric field present in coaxial resonator, there is also a magnetic field present which is in a coupling relation with the electric field, the lines of force of this field being in a perpendicular relation with the lines of force of the electric field.

To enable the establishment of fields in such a relation, it is necessary to have the dimensions of the cavity correct for a desired frequency. For example, a filter operating at 1500 mc. could employ 1½" cubes, the

walls being approximately $\frac{1}{16}$ " thick and the slugs should be approximately $\frac{3}{8}$ " in diameter. The dimensions of the cube are important as those skilled in the art will realize, while the thickness of the walls and diameter of the slugs are variables that will depend on the skin-effect requirement and desired amount of coupling from the resonator at the operating frequency. Tuning slug 6 is adjustable for frequency selection and aperture 11, which mates with aperture 12, sets the coefficient of coupling to the adjacent resonator, the approximate design equations for coefficient of coupling between adjacent resonators being

$$K_{\text{adjacent}} = .7 \frac{BW_{3 \text{ db}}}{f_0}$$

Coaxial resonators 1, 2, 3, 4, and 5 may be held together by soldering, bolt and nuts, or screws, or by some other suitable means. If desired, the walls of the several cavities may be made integral. Coupling between adjacent coaxial resonators 1, 2, 3, 4, and 5 is accomplished by apertures, such as apertures 11 and 12 in the walls of coaxial resonators 1 and 2. The arrangement shown in Fig. 1 of the drawing is such that there is magnetic and electric coupling progressing alternately from resonator 1 to resonator 5 of the filter. This arrangement of coupling by alternate fields reduces the direct feedthrough of frequency, on say the magnetic field, which would tend to reduce the skirt selectivity of the filter. In other words, by alternating the adjacent resonator coupling between magnetic and electric fields, it is necessary for the energy in the magnetic field to be transferred to the electric field by a resonator before it can pass on to the next resonator so that the energy must pass selectively from one cavity to another giving an overall optimum selectivity. Using the same line of reasoning, it can be seen that the input aperture 13 and the output aperture 14 should follow the same pattern. It is conceivable that the location of apertures 13 and 14 could be such as not to follow this pattern with the only result being that far out on the skirts of the response the attenuation may not be as great as possible.

The location of the strongest electric field is in the region 15 near the end of tuning slug 6 and the strongest magnetic field is in the region 16 far from the end of tuning slug 6. To obtain maximum results from the filter, it is helpful to locate the adjacent coupling apertures, such as 11 and 12, and apertures 13 and 14 in these regions of maximum field strength. However, the performance of the filter is not dependent upon locating the apertures in the region of the strongest fields as long as coupling means are located adjacent to the fields. Apertures 11 and 12 when located adjacent the magnetic field may be oval or rectangular in shape with the longer dimension in parallel relation with magnetic lines of force, and when such apertures are located adjacent the electric field, they may be circular in shape although other shapes may be employed.

A filter as described to this point is one which contains poles, but no zeros, much like a constant- k configuration in low frequency work. The response curve of such a VHF, UHF, and microwave band pass filter will be seen in Fig. 3 curve A. It will be noticed that this arrangement alone is not as good as may be desired since the rate of cut-off as shown by the slope may not be as sharp as required. Coupling separately alternate resonators as shown in Fig. 1 accomplishes this object of my invention, resulting in curve B, Fig. 3. A coupling line 17 with its end probes 21 and 21a is used to produce a resultant inductive coupling between resonators 1 and 3, while a coupling line 18 with its end probes 22 and 22a produces capacitive coupling between resonators 1 and 3. Coupling lines 19 and 20 and their end probes perform the same function in connection with resonators 3 and 5. As was herein mentioned, the electrical length of the coupling lines 17, 18 and 19, 20 will depend upon probe

combinations therein, but in general will be some multiple of a quarter wavelength long.

One of the four different combinations of coupling probes and line lengths is shown in resonators 1 and 3 of Fig. 1 wherein the magnetic probes 21 and 21a, connected to the one-quarter wavelength long coupling line 17, and the electric probes 22 and 22a, connected to the one-quarter wavelength long coupling line 18, are in such a physical arrangement that each current injected into resonator 3, due to the voltage across resonator 1 is shifted -90° and $+90^\circ$, respectively, with respect to the voltage across resonator 1. This is one of the fundamental requirements that must be satisfied by a pair of coupling lines and their end probes. Another fundamental requirement is that one of the aforementioned 90° currents increases in magnitude in direct proportion to frequency, and the other 90° current decreases in magnitude in direct proportion to frequency.

There is in addition a fundamental requirement upon the adjacent or intermediate resonator couplings which may be stated as follows: The phase relation between the net current injected into resonator 3 by the alternate resonator coupling and the net current injected into resonator 3 by the intermediate resonator coupling must be such that at the desired frequency of infinite attenuation they are opposing in phase. Thus, at these frequencies where the phase of the waves are 180° out of phase, by proper adjustment of the amount of the adjacent and intermediate coupling, it is possible to completely cancel both the magnetic and electric propagation, thereby producing zeros or inserting infinite attenuation points, such as 23 on curve B, Fig. 3. The preceding equation gave the approximate required value for the adjacent couplings in order to produce a desired pass band width, and the below equation gives the approximate required value for the alternate couplings

$$K_{\text{alternate}} = \frac{1}{2 \left(\frac{BW_{\infty}}{BW_{3 \text{ db}}} \right)^{\lambda} + 1}$$

The second infinite attenuation points 24 on curve B are produced in a similar manner, by employing coupling lines 19 and 20 cooperating with coaxial resonators 3, 4 and 5 wherein the various phase relations are identical. Through the frequency band which the filter is operative, the capacitive type coupling coefficient of coupling line 18 and the inductive type coupling coefficient of coupling line 17 are essentially constant and equal in magnitude.

Fig. 4 in the drawing illustrates another embodiment of my invention wherein the individual cavity resonators are identical with the coaxial resonators 1, 2, 3, 4, and 5 discussed above. The difference between the embodiments is the arrangement whereby the adjacent coupling apertures 25, 26, 27, 28 are situated alternately in an electric field region and a magnetic field region, with both the input aperture 29 and output aperture 30 of the filter being situated adjacent a magnetic field region. The results obtained with this arrangement are substantially identical with that of the aforementioned arrangement with possibly the exception that the attenuation far from the pass band is slightly decreased due to the adjacent coupling aperture 28 and the output aperture 30 being in the region of the same energy field for reasons previously mentioned. This apparent disadvantage of the coupling arrangement in coaxial resonator 31 may be readily overcome by shifting aperture 30 vertically in order that it may couple from the electric field rather than the magnetic field thus reducing the possibility of direct feed-through of unwanted frequency on the magnetic field. Voltage in coupling lines 32, 33 and 34, 35 in cooperation with the voltage passing through resonators 2 and 4, respectively, produces the points of infinite attenuation as discussed with reference to Figs. 1 and 2 of the drawing.

The combinations of magnetic probes 36 and 36a and electric probes 37 and 37a with their respective coupling lines 33 and 32, are physically arranged to satisfy the phase requirements as set forth in the embodiment shown in Fig. 1 by having the length of coupling line 32 the same as the length of coupling line 33 with the total length of each line being some odd multiple of a quarter wavelength.

Still another embodiment of my invention is shown in Fig. 5 of the drawing. This variation operates on the same principle as the previous embodiment as to the development of zeros. The cavity resonators are rectangular waveguides 38, 39, 40, 41, and 42 which operate in the TE_{0,1} mode. Physical dimensions of the individual waveguide resonators are approximately 0.707λ long, 0.707λ wide, where λ is the free space wavelength, and the height being chosen to satisfy the requirement of electric field strength. As is known the electric field is concentrated between points 43 and 44 in a typical waveguide resonator of this type while the magnetic field is circular in cross section, concentric with the concentrated electric field.

In the arrangement indicated, the input to the filter is by means of loop 45 through aperture 46 in the wall adjacent to the magnetic field of waveguide resonator 38. The voltage oscillates between the magnetic field and the electric field with part of the electric field being coupled to waveguide resonator 39 through circular aperture 44. A resulting electric and magnetic field oscillation results in waveguide resonator 39 and part of the magnetic field is coupled to waveguide resonator 40 via a rectangular slit aperture 48 through the wall therein. This alternating process from electric to magnetic coupling continues progressively through the filter until the selected energy is coupled out of the system through aperture 49 in the electric field of waveguide resonator 42. The zeros in the transfer characteristic are produced as heretofore explained in connection with Fig. 1 by employing coupling lines 50, 51, 52, and 53 and the associated probes. With the probes as shown, lines 50 and 51 must be an identical odd number of quarter wavelengths long. Lines 52 and 53 must also be an identical odd number of quarter wavelengths long.

A further embodiment of my invention is shown in Fig. 6 which illustrates three adjacent waveguide resonators 54, 55, and 56, the dimensions of which are discussed in connection with Fig. 5, with adjacent coupling provided by quarter wavelength coaxial lines 58 and 59.

Production of zeros is accomplished by employing the third of the four coupling probe combinations hereinbefore mentioned. As shown because of the opposite sense of the coupling loops 64 and 64a, the coupling lines 62 and 63, with their associated probes 64 and 64a and 65 and 65a, must differ in length by a half wavelength. The extra half wavelength may be placed in the coupling line 62 connecting the magnetic probes. This arrangement then establishes, in accord with the fundamental phase requirements outlined in the discussion of Fig. 1, the requirement that coupling loops 61 and 60 be oppositely bent as shown.

A fourth coupling combination may be achieved by placing the required extra half wavelength in the coupling line 63 connecting the capacitive probes. This will require one coupling loop 60 or 61 to be reversed from the position shown to establish the proper phase relation as outlined in the discussion of Fig. 1 which allows achievement of the desired filter having a high rate of cut-off.

Fig. 7 illustrates another embodiment wherein waveguide resonators 64, 65, and 66 are adjacently coupled by quarter wavelength waveguides 67 and 68. Alternate resonator coupling is provided through coupling lines 69 and 70 in cooperation with magnetic coupling probes 71 and 71a and capacitive coupling probes 72 and 72a. The physical arrangements of these magnetic probes 71 and 71a are in the opposite sense with reference to their

respective capacitive coupling probes 72 and 72a, therefore, the length of the coupling lines 69 and 70 must differ in length by one-half wavelength to properly attain the aforementioned filter results. Because adjacent coupling waveguides 67 and 68 are both of the positive mutual inductance type, it is necessary to add the required extra half wavelength in the coupling line 70 joining the capacitive probes 72 and 72a in order that the required filter results are obtained.

Although I have shown and described certain specific embodiments of my invention, I am fully aware that many modifications thereof are possible. Therefore, this description is made by way of example and not as a limitation to the scope of my invention.

15 I claim:

1. A band pass filter comprising a plurality of cavity resonators numbering at least three, means coupling said resonators in series, input terminal means to introduce energy into the series of resonators, output terminal means 20 to remove energy from said series of resonators, said series of resonators including two groups, one of said groups consisting of the odd ones of said series of resonators and the other of said groups consisting of the even ones of said series of resonators, and aperiodic means coupling the members of one of said groups in tandem.

2. A band pass filter according to claim 1, wherein said means coupling said resonators in series includes walls of said resonators having apertures therein, certain of said apertures being configured and disposed for coupling with 30 the electric field and other of said apertures being configured and disposed for coupling with the magnetic field of said resonators.

3. A band pass filter according to claim 2, wherein said apertures coupled with the electric field are circular 35 and said apertures coupled with the magnetic field are elongated in a direction parallel to the magnetic lines of force.

4. A band pass filter according to claim 2, wherein the energy in each of said resonators is coupled between 40 the electric and magnetic fields and said means coupling said resonators in series couples the energy progressively between the electric and magnetic fields of said series of resonators.

5. A band pass filter according to claim 2, wherein said means coupling said resonators in series includes coaxial 45 transmission lines having a length equal to odd multiples of one-quarter wavelength.

6. A band pass filter according to claim 2, wherein said means coupling said resonators in series includes waveguide couplers having a length equal to odd multiples of one-quarter wavelength.

7. A band pass filter according to claim 1, wherein said input terminal means is disposed to be coupled with the electric field of the first of said series of resonators and said output terminal means is disposed to be coupled with the magnetic field of the last of said series of resonators.

8. A band pass filter according to claim 7, wherein said input terminal means comprises a probe extending into the first of said series of resonators for capacitive coupling to the electric field therein while said output terminal means comprises a loop extending into the last of said series of resonators for inductive coupling to the magnetic field therein.

65 9. A band pass filter according to claim 7, wherein said input terminal means comprises a loop extending into the first of said series of resonators for inductive coupling to the magnetic field therein while said output terminal means comprises a probe extending into the last of said series of resonators for capacitive coupling to the electric field therein.

10. A band pass filter according to claim 1, wherein said aperiodic means includes a pair of coupling lines, one of said lines having capacitive probes and the other of said lines having inductive loops for capacitive and

inductive coupling of energy between the members of said one of said groups.

11. A band pass filter according to claim 10, wherein said coupling lines include coaxial coupling lines having a length equal to odd multiples of one-quarter wavelength long.

12. A band pass filter according to claim 1, wherein said resonators are coaxial resonators including a cylindrical tuning slug.

13. A band pass filter according to claim 1, wherein said resonators are rectangular waveguide resonators.

14. A band pass filter comprising five coaxial resonators each including a cylindrical tuning slug, means coupling said resonators in series, input terminal means to introduce signal to said series of resonators, output terminal means to remove signal from said series of resonators, said series of resonators including two groups, one of said groups consisting of the odd ones of said series of resonators and the other of said groups consisting of the even ones of said series of resonators, and aperiodic means coupling the members of one of said groups in tandem.

15. A band pass filter according to claim 14, wherein each of said resonators encompass a magnetic field and electric field in coupling relation with each other and said means coupling said resonators in series are so disposed with respect to the magnetic and electric fields of said resonators that the energy traverses said series of resonators alternately on the electric and magnetic fields of said resonators, said input terminal means being disposed in coupling relation with the electric field of the first of said series of resonators and said output terminal means being disposed in coupling relation with the magnetic field of the last of said series of resonators.

16. A band pass filter according to claim 15, wherein said aperiodic means comprises two pairs of coaxial coupling lines having a length equal to an odd multiple of one-quarter wavelength, one pair of said coupling lines coupling the first and the third resonators while the other pair of said coupling lines couple the third and the fifth resonators, one coupling line of each pair of coupling lines having capacitive coupling probes and the other coupling line of each pair of coupling lines having inductive coupling probes for magnetic and electric field energy coupling between the members of said one of said groups.

17. A band pass filter comprising five rectangular waveguide resonators, means coupling said resonators in series, input terminal means to introduce signal to said series of resonators, output terminal means to remove

signal from said series of resonators, said series of resonators including two groups, one of said groups consisting of the odd ones of said series of resonators and the other of said groups consisting of the even ones of said series of resonators, and aperiodic means coupling the members of one of said groups in tandem.

18. A band pass filter according to claim 17, wherein each of said resonators encompass a magnetic field and an electric field in coupling relation with each other and said means coupling said resonators in series are so disposed with respect to the magnetic and electric fields of said resonators that the energy traverses said series of resonators alternately on the electric and magnetic fields of said resonators, said input terminal means being disposed in coupling relation with the electric field of the first of said series of resonators and said output terminal means being disposed in coupling relation with the magnetic field of the last of said series of resonators.

19. A band pass filter according to claim 18, wherein said aperiodic means comprises two pairs of coaxial coupling lines having a length equal to an odd multiple of one-quarter wavelength, one pair of said coupling lines coupling the first and the third resonators while the other pair of said coupling lines couple the third and the fifth resonators, one coupling line of each pair of coupling lines having capacitive coupling probes and the other coupling line of each pair of coupling lines having inductive coupling loops for magnetic and electric field energy coupling between the members of said one of said groups.
